UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

NUT MACHINE.

Application filed August 9, 1924. Serial No. 731,151.

My invention relates to a new and improved machine for making nuts and other articles having an opening therethrough as well as the means and methods by which such nuts and articles are produced.

It is the object of this invention among other things, to automatically produce from cold stock nuts and other articles having an opening therethrough, by a method wherein there are the minimum number of operations and waste of material, if any, and to provide mechanism whereby these desirable results may be obtained, that may be readily adapted for use in a heading, upsetting machine or the like of well known and conventional form.

To these and other ends my invention consists in the method and means for making nuts and articles having an opening therethrough and to mechanism for producing these results having certain details of construction and combinations of parts as will be hereinafter described and more particularly pointed out in claims.

Referring to the drawings, in which like numerals of reference designate like parts in the several figures;

Figure 1 is a fragmentary plan view of one end of a header or upsetting machine or the like having my improved mechanism connected therewith;

Figure 2 is a sectional elevation thereof taken generally upon line 2—2 of Figure 1;

Figure 3 is a sectional elevation thereof taken generally upon line 3—3 of Figure 1;

Figure 4 is a side elevation of the end portion of the machine looking toward the top of Figure 1 with the parts in section taken generally upon line 2—2 of Figure 1;

Figures 5 and 6 are fragmentary side elevations of the stripping mechanism with the piercing punch shown in two of its relative positions therewith;

Figure 7 is an enlarged front elevation of the stripper head;

Figure 8 is a fragmentary view of the front portion of one of the pair of dies showing a wire rod therein just before the first, or upsetting operation;

Figure 9 is a front elevation of the upsetting dies;

Figure 10 is a view similar to Figure 8 showing in section the forward end of the

rod after the first upsetting operation has been performed thereon;

Figure 11 is an end view thereof and also the dies;

Figure 12 is a view similar to Figure 10 showing in sectional view the partially completed blank after the operation of the nipping punch thereon;

Figure 13 is a front view thereof and also the dies;

Figure 14 is a view of one of the dies with a portion of the wire rod therein, in the position placed by the piercing punch and ready to be advanced for the next set of operations thereon.

Figures 15 and 16 are front and side elevations respectively of the upsetting punch;

Figures 17 and 18 are front and side elevations respectively, of the nipping punch;

Figures 19 and 20 are front and side elevations respectively of the piercing punch, having in the latter view a section of a nut as it appears when removed from the dies;

Figure 20a is a cross section on the line 20a—20a of Fig. 13;

Figure 21, views of several forms of nuts and articles that may be produced by my improved method and mechanism;

Figure 22 is an enlarged front elevation of the stripper head having a trimming die connected therewith;

Figure 23 is a fragmentary plan view thereof;

Figure 24 is a fragmentary side elevation thereof; and

Figure 25 is an elevation of the punch block with a nut thereon in engagement with the pressure die.

In this invention, an article is formed upon the end of a wire rod and then a hole formed therein of substantially the same size and cross section as that of the wire rod by forcing the same rearwardly from the article so that the portion of the rod formerly forming the center of the article still remains a part thereof, to become a portion of the next succeeding article formed. As herein shown, the article is formed on the end of a wire rod circular in cross section, but rods of other cross section may be used with this method and means with equal advantage if the shape and form of the articles to be produced are more readily adapted

for such rod structure. Thus a succession of articles is produced from a single rod without waste of material or at least any waste of substantial amount.

5 In the embodiment of the means herein disclosed, whereby my new and improved method is practiced, I disclose the same as associated with a heading, upsetting machine or the like, the body of which is designated 10 having a gate 11 movable therein, a punch slide 12 which is vertically movable in the gate and receiving motion from a rock shaft 13 through a connection mechanism 14, of any well known type but forming no part 15 of this invention. In one end of the body 10 is a pocket 15 within which is mounted a die block 16 having a cap or cover 17 hinged thereto and between which is movably mounted the dies 18. The wire is fed into 20 the machine by a feed mechanism 19 having as a part thereof the rolls 20 and 21 which derive an intermittent rotary movement from the shaft 13 through the link 22 that is connected at one end to an arm 23 on the 25 rock shaft 13 and at the other end with the rock arm 24 on the same shaft as the feed roll 21. The wire rod 25 is advanced between the dies by the rolls 20 and 21 through the quill 26 and the back of the die block 16 as is 30 usual, its innermost position being determined by the movable stop 27. The dies are closed in the die block by the toggle mechanism 28.

All of the mechanism above described is 35 old and well known in the art and requires no further detailed description herein, with the exception of the link joint between the link 22 and rock arm 24 which is part of this invention. The end of this link, projects between the ears 34 upon the rock arm 24 and is slidably connected therewith by a pin 29 which projects through a slot 30 in the link. A spring 31 between the post 32 in the rock arm 24 and post 33 in the 40 link exerts its extension so as to hold the pin at that end of the slot nearest the arm 23, as shown in Figure 4. Thus the parts are so located relatively that the wire rod 25 may be advanced into the machine between the dies by the feed rolls. A slight 45 reverse movement of these feed rolls is permissible by the action of the wire rod thereon and for a purpose hereinafter to be described, at which time the pin 29 will travel 50 in the slot 30 without imparting movement to the link. On the face of the punch slide is a punch holder 35, as is usual, and within which I have mounted an upsetting punch 36, a nipping punch 37 and a punch block 38 within which is a piercing punch 39 secured by a screw 40 or the like.

In the drawings herein the punches and dies are so shaped and associated as to form a hexagonal nut. The upsetting punch 36 55 has a hexagonal face 41 and of substan-

tially the same dimensions as that of the finished nut, with a conical tip 42 concentric therewith, and an annular recess 43 surrounding the face 41. The nipping punch 37 is constructed with a recess 44 in its face 70 that is substantially the same shape in cross section as that of the finished nut, and surrounding this recess is a depression 45, the inside wall of which is tapered downwardly away from the face of the nipping punch 75 so as to form a knife edge, substantially as shown in Figure 18. In operation the wire rod 25 is advanced between the dies until the inner end thereof projects in front of the face of the dies, a distance, substantially 80 as shown in Figure 8, that is, until there is sufficient projecting stock to fill the cavity 46 in and between the dies. The punch 36 is now brought into contact with this projecting end and upsets the stock so that it 85 fills the cavity 46 and the tip 42 forms the depression 47 in the end of the blank 48 substantially as shown in Figure 10. As the nut is hexagonal in shape, the metal flows over the face of the dies substantially as 90 shown in Figure 11, which overflow is accommodated in the annular recess 43 of the punch 36. This overflow will not occur if the cavity 46 in the dies is round. The base of the tip 42 is substantially the same diameter as the hole through the finished nut and preferably is of such length that the pointed end thereof passes into the blank, a distance 95 equal to the thickness of the finished nut. It can, with equal facility, if desired, project into the blank, a distance greater or less than the thickness of the nut, this depending in some measure upon the character of the material from which the articles are made as well as its hardness and volume 100 of material to be upset by the operations.

The nipping punch 37 is next moved forward until its front face almost engages the face of the dies 18, thus scoring the blank and particularly the fin or flash 49 formed around the edge thereof at 50. This scoring insures the breaking of the fin or flash from the blank at the outer edges thereof and upon a line coincident with the side faces of the finished nut, so, that when broken off, there is no rough or unfinished edge at the point of the break. Thereafter the piercing punch 39, the tip 51 of which is substantially the same diameter as the wire rod 25 and the hole 52 of the finished blank 53, is advanced so the end thereof passes through the blank to a point below the bottom of the cavity 46, that is a distance greater than the thickness of the nut. During this action of the piercing punch the stock in front of the tip 51 is forced rearwardly out of the blank to a position substantially as shown in Figure 14. The feed rolls 20 and 21 permit this rearward movement of the wire rod 25 by reason of the slip connection between the 120 125 130

link 22 and rock arm 24, in the manner above described. The burden upon the piercing punch 39 is very much reduced by reason of the depression 47 formed in the end of the 5 blank by the punch 36. By this means, the amount of metal to be displaced in the forming of the article is reduced to the minimum.

Near the face of the tip 51 of the piercing punch 39 I have provided an annular groove 10 52 of limited depth and into which the metal of the blank flows during the piercing operation sufficient to hold the same on the punch when it is withdrawn from the dies. Then the blank 54 remains on the piercing 15 punch, a cross section of which is shown in Figure 20. The means by which the dies 18 are held together during this upsetting operation is so timed that they open slightly at the same instant as the piercing punch 39 20 starts to pierce the hole in the nut, which allows the wire rod to be readily pushed back between the dies, and the instant the piercing punch starts to withdraw, the dies are opened further for the purpose of freeing 25 the contact on the outer surface of the nut in the cavity of the dies so that the nut will readily be withdrawn on the punch out of the cavity in the dies. Fixed below the dies 18 is a stripper mechanism comprising 30 a frame 55 having a rearwardly projecting plate 56 thereon through which one or more screws 57 pass to separably secure the frame to a fixed part.

Slidably mounted in the frame 55 in radial paths around a common center are three slides 58 that are moved inwardly by a spring 59 secured at one end. The inner ends of these stripper slides are so formed that when in their innermost positions and 40 in contact with each other an hexagonal opening 60 is formed therebetween of the same size, or slightly less than that of the finished nut and formed with an open flaring throat 61. This stripper mechanism is located directly below the dies so that when 45 the upsetting punch is brought into contact with the end of the wire rod 25, the nut formed by the previous operations of the punches, now upon the piercing punch 39, 50 is projected through the opening 60. While passing therethrough the flash or fin 49 thereon is broken off at the scoring line and the ruptured surface is smoothed over and planished by the side walls of the hexagonal opening 60, the spring 59 yielding slightly 55 to permit this motion. On the return movement of the gate and the piercing punch 39 the rear face of the nut engages the rear square edges of the slide 58 and strips the 60 same from the punch. The nut now being free, drops through the channel 62 in the rear of the stripper frame as shown in Figure 6, into a box or receptacle, conveniently arranged to receive it.

In Figure 21 I have shown four of many 65 shaped articles, as samples of the work that may be produced by my improved method and mechanism. In all cases the cavity 46 in the dies, and the opening 60 in the stripper mechanism are shaped to correspond 70 with that of the finished article. If the article is round there will be no flash or fin and the nipping punch may be omitted.

By this method and mechanism, the upsetting of the metal and the piercing of the 75 hole are accomplished by individual and separate solid punches and blows, the small amount of surplus metal projecting out of the cavity in the dies is nipped or reduced 80 in thickness directly around the edge of the said cavity to facilitate the breaking off of the very small pieces of scrap. The third blow is that of piercing the hole and driving the wire rod back between the dies, as the article is made on the end of the wire 85 rod and integral therewith until the hole is pierced, which severs the wire rod from the nut. The opening of the dies is important 90 for two reasons:—first, it allows the wire rod to be readily pushed back, and secondly, it frees the clinging contact the outer surface of the nut would naturally have in the recess of the dies, so that as the piercing punch returns, the nut will be withdrawn on the punch out of the cavity in the dies. The punches are then lowered so that the 95 upsetting punch is again in line with the wire rod. In the meantime this wire rod is advanced sufficiently to make the next nut and the gate with the punches is advanced 100 and while upsetting the wire rod the last formed nut or blank is pushed through the stripper mechanism which removes the flash or fin and also strips it off the piercing punch on its return.

The method of making the nut with a small amount of flash and oversupply of metal for the cavity in the dies preserves the life of the dies and punches. If the punch should enter the cavity absolutely tight, 110 which would be necessary to prevent the formation of a flash or fin, it would burst the dies, or break the punch. Therefore, in the upsetting operation the punch does not enter the cavity in the dies, and any little variation of the amount of metal upset will be taken care of in a flash which is only a trifle in amount but by reason thereof extends the life of the tools and increases the efficiency thereof.

For some classes of work it is desirable 115 that the nut blank be trimmed, in which case a trimming die 63 is secured to the frame 55 by the screws 64 or the like, with the trimming opening 66 therethrough substantially concentric with the stripper opening 60. This die 63 trims the nut as it is passed 120 through the opening 66 on the punch 39 and

is stripped therefrom by the stripper slides 58 upon the return movement of the punch in the manner above described.

At times, with some kinds of metal and especially after the dies have been used for some time, a slight fin is formed upon the face of the nut where the dies meet. Usually this fin is so slight as to be unobjectionable and is readily removed by a subsequent tumbling process. However, I provide means in my improved machine to remove this fin without additional movement of any of the parts. This means comprises a die 67 that has an opening therein to allow for the movement of the end of the punch 39, held in the frame 55 by the screw 68, or the like, and provided with a work face 69. This die 67 is so positioned that the work face is held in alignment with the fin on the face of the nut, which contacts therewith and is compressed thereby, so that the face of the nut is thereby made entirely smooth. While I have shown this die 67 as associated with the frame 55 in Figures 22, 23 and 24, to which the trimming die 63 is secured, it is obvious that it may be associated equally as well with the frame 55, as illustrated in Figures 5, 6 and 7.

Having described my invention, what I claim as new and desire to secure by Letters Patent, is:

1. In an apparatus of the character described; companion dies movable toward and away from each other, in the outer face of which is a cavity, and extending rearwardly therethrough from the bottom of the cavity is an opening of substantially the same cross section as the rod from which the articles are produced; a punch for upsetting the projecting portion of a rod held between and by the dies, to fill said cavity and at the same time form a depression in the outer face of the upset portion; and another punch separate from the one first mentioned for extending the said depression and thereby forming a hole in the upset portion of the rod within the cavity that forces the material engaged thereby longitudinally between the said dies without severing the same from the rod, said dies being held together under lateral pressure while the first mentioned punch is in engagement with the rod and separated slightly when the second mentioned punch is forming the opening.

2. In an apparatus of the character described; companion dies movable toward and away from each other, in the outer face of which is a cavity, and extending rearwardly therethrough from the bottom of the cavity is an opening of substantially the same cross section as the rod from which the articles are produced; a punch for upsetting the projecting portion of a rod held between and by the dies, to fill said cavity and at the same time form a depression in the outer

face of the upset portion; and another punch separate from the one first mentioned for extending the said depression and thereby forming a hole in the upset portion of the rod within the cavity that forces the material engaged thereby longitudinally between the said dies without severing the same from the rod or enlarging the diameter thereof, said dies being held together under lateral pressure while the first mentioned punch is in engagement with the rod and separated slightly when the second mentioned punch is forming the opening.

3. In an apparatus of the character described; a pair of dies movable toward and away from each other that form a separable workholder, in the outer face of which is a closed cavity when the dies are in contact with each other, and extending rearwardly therethrough from the bottom of the cavity is an opening of substantially the same cross section as the rod, from which the articles are produced; a punch for upsetting the projecting portion of a rod held rigidly between the dies to fill said closed cavity and form a depression in the outer face of the upset portion of the rod within such cavity, this depression being of substantial relative depth and displacing a portion of the rod necessary to form the hole through the finished article; and another punch separate from the one first mentioned for extending the said depression and thereby forming a hole in the upset portion of the rod within such cavity that forces the material engaged thereby and the rod between the dies rearwardly and away from the cavity without securing the same from the rod, said dies being held together under lateral pressure during the upsetting of the rod end and separated a limited distance while the hole is being formed in the upset portion, the diameter of the rod end after the action of the second punch thereon, that is in and between the dies, being the same as before the upsetting operation.

4. In mechanism of the character described; a pair of dies movable toward and away from each other having a cavity in their outer faces; a punch for upsetting the projecting portion of the rod held between and by the dies against endwise movement so that the same will fill said cavity; another punch for forming an opening in said upset portion, of substantially the same diameter as the rod, that forces the material engaged thereby longitudinally between the dies without severing the same from the rod or enlarging the diameter thereof, the dies being held so that lateral pressure is applied to the rod while the first mentioned punch is engaging the rod and separated slightly when the second mentioned punch is forming the opening; and means for scoring the flash or fin upon the upset por-

- tion, if any, while the upset portion is still in said cavity; and means for removing from the article such scored flash or fin after having been taken from said cavity.
5. In mechanism of the character described; a pair of dies, each having a cavity in the face thereof which unite when the dies are together to form a single cavity; a punch for upsetting the projecting portion of a rod held between the dies, the upset portion filling that part of the cavity adjacent to the walls thereof and having a depression, substantially conical in shape, in the outer face thereof approximately the same depth as the cavity and another punch for forming an opening in the upset portion that forces the material engaged thereby longitudinally between the dies without severing the same from the rod or enlarging its diameter, said dies being held together under lateral pressure while the first mentioned punch is engaging the rod and separated slightly when the second mentioned punch is forming the opening.
25. 6. In mechanism of the character described; companion dies, each of which has a cavity in its face which unite to form a single cavity when the dies are in contact with each other; a punch for upsetting that portion of a rod held between the dies and projecting through said cavity; and another punch for forming an opening in the upset portion that forces the material engaged thereby longitudinally between the dies without severing the same from the rod, the dies being held together under lateral pressure while the first mentioned punch is engaging the rod and separated slightly when the second punch is forming the opening, the second mentioned punch having a recess therein, into which the metal flows while the punch is in contact therewith, thereby forming an intermeshing engagement between the punch and article which is maintained during the withdrawal of the punch.
7. In mechanism of the character described; companion dies, each of which has a cavity in its face which unite to form a single cavity when the dies are in contact with each other; a punch for upsetting that portion of a rod held between the dies and projecting through said cavity; and another punch having a surface thereon of less cross sectional area than that of the opening in the upset portion, the last mentioned punch forming an opening in the upset portion and forcing the material engaged thereby longitudinally between the dies without severing the same from the rod and also causing the metal to flow into that portion of the punch of less cross sectional area than the diameter of the opening, whereby an intermeshing engagement is automatically formed between the punch and blank which is maintained during the withdrawal of the article from the die, the dies being held together under lateral pressure while the first punch is operating upon the rod, and separated slightly while the second mentioned punch is in operation.
8. In mechanism of the character described; a pair of dies having a cavity therein; a plurality of punches separate from each other; means for moving said punches so that the axis of each punch is successively moved into a position substantially coincident with the work receiving opening in the dies, the first of said punches upsetting a projecting portion of a rod held between the dies to fill said cavity, another of said punches scores the flash, if any, formed around the outer face of the upset portion, and another of said punches forming an opening in the upset portion and severing the same from the rod, the movement of the rod between the dies being in a straight path toward said cavity and then in a similar but a reverse straight path.
9. In mechanism of the character described; a pair of dies having a cavity therein; a plurality of punches separate from each other; means for moving the punches so that the axis of each punch is successively and substantially coincident with the work receiving opening in the dies, the first of said punches upsetting a projecting portion of a rod held between the dies to fill said cavity, another of said punches scores the flash, if any, formed around the outer face of the upset portion, and another of said punches forming an opening in the upset portion and severing the same from the rod, without enlarging the diameter thereof, said last mentioned punch also withdrawing the article from the cavity, the movement of the rod through the dies being intermittent but in a straight path substantially parallel to the axis of the rod.
10. In mechanism of the character described; a separable workholder having a cavity therein; a plurality of punches; means for moving said punches so that the axis of each punch is successively and substantially coincident with the work receiving opening in the workholder, the first of said punches upsetting a projecting portion of a rod held between the parts of the workholder to fill said cavity, another of said punches scores the flash, if any, formed around the outer face of the upset portion, and another of said punches forming an opening in the upset portion and severing the same from the rod, the last mentioned punch also withdrawing the article from the cavity; and means for stripping the article from the last mentioned punch when the axis of one of the other punches is substantially coincident with that of the cavity, said stripping means performing its function while the first mentioned punch is be-

ing withdrawn after an upsetting operation.

11. In mechanism for forming an article from a rod in a workholder; means for withdrawing the article so formed from said workholder, comprising a punch or the like; means for stripping the article from said punch, comprising mechanism, independent of the workholder and punch, having members movable radially from a common center and so formed as to have an opening around said common center, which members yield when an article on a punch is moved therethrough in one direction but remain rigid while the punch is being moved in the opposite direction and by reason thereof stripping the article from the punch.

12. In mechanism for forming an article from a rod in a workholder; means for withdrawing the article so formed from said workholder, comprising a punch or the like; and means for stripping the article from said punch, comprising a mechanism having members slidable radially from a common center and so shaped as to have an opening around said common center, which members yield when an article on the punch is moved therethrough in one direction but remain rigid while the punch is being moved in the opposite direction and by reason thereof stripping the article from the punch.

13. In mechanism for forming an article from a rod in a workholder; means for withdrawing the article so formed from said workholder, comprising a punch or the like; and means for stripping the article from said punch, comprising a mechanism having members slidable radially from a common center and so formed as to have an opening around said common center, which members yield when an article on a punch is moved therethrough in one direction but remain rigid while the punch is being moved in the opposite direction and by reason thereof stripping the article from the punch.

14. In mechanism for forming an article from a rod in a workholder; means for withdrawing the article so formed from the workholder, comprising a punch or the like; and means for stripping the article from the punch, comprising a mechanism having a frame, a plurality of slides mounted therein about a common center, each slide being so formed that when in contact with the other slides an opening is formed therebetween, and spring means for moving the slides in one direction.

15. In mechanism for forming an article from a rod in a workholder; means for withdrawing the article so formed from the workholder, comprising a punch or the like; and means for stripping the article from the punch, comprising a mechanism having a frame, a plurality of slides mounted thereabout a common center, each slide being

so formed that when in contact with the other slides an opening is formed therebetween with an outwardly flaring throat, and spring means for moving the slides in one direction.

16. In mechanism of the character described; a workholder having a cavity therein; a punch for upsetting the projecting portion of a rod held between the parts of the workholder; another punch separate from the first mentioned punch for forming an opening in said upset portion which carries the article with it when moving away from the workholder; and means for stripping the article from the second mentioned punch comprising a mechanism having members slidable radially toward and away from a common center and so formed as to provide an opening around said common center, which members yield when an article with the punch is moved in one direction through said opening and rigid while the punch is being moved in the opposite direction, the said article passing through said opening at approximately the same time that the first mentioned punch is upsetting the projecting portion of the rod for the article next to be formed in the workholder.

17. In mechanism of the character described; a separable workholder having a cavity therein; a punch for upsetting the projecting portion of a rod held between the parts of the workholder, to fill said cavity; another punch separate from the first mentioned punch, for forming an opening in said upset portion that forces the material engaged thereby between the parts of the workholder without severing the same from the rod, the parts of the workholder being held together under lateral pressure while the first mentioned punch is engaging the rod and separated slightly when the second mentioned punch is forming the opening, this latter punch during its withdrawal carrying with it, and out of said cavity, the article formed therein; and means for trimming said article after it has been removed from the workholder.

18. In mechanism of the character described; a separable workholder having a cavity therein; a punch for upsetting the projecting portion of a rod held between the parts of the workholder, to fill said cavity; another punch separate from the first mentioned punch, for forming an opening in said upset portion that forces the material engaged thereby between the parts of the workholder without severing the same from the rod, the parts of the workholder being held together under lateral pressure while the first mentioned punch is engaging the rod and separated slightly when the second mentioned punch is forming the opening, the second mentioned punch during its withdrawal carrying with it, and out of said cavity,

- the article formed therein; and means for trimming said article after it has been removed from the workholder at approximately the same time that the first mentioned 5 punch is upsetting the projecting portion of the rod for the article next to be formed.
19. In mechanism of the character described; a separable workholder having a cavity therein; a punch for upsetting the 10 projecting portion of a rod held between the parts of the workholder, to fill said cavity; another punch separate from the first mentioned punch, for forming an opening in said upset portion that forces the 15 material engaged thereby between the parts of the workholder without severing the same from the rod, the parts of the workholder being held together under lateral pressure while the first mentioned punch is engaging 20 the rod and separated slightly when the last mentioned punch is forming the opening; and means for applying pressure to that face of the article exposed at the end of the punch after the same has been removed from the 25 cavity.
20. In mechanism of the character described; a separable workholder having a cavity therein; a punch for upsetting the projecting portion of a rod held between the 30 parts of the workholder, to fill said cavity; another punch separate from the first mentioned punch, for forming an opening in said upset portion that forces the material engaged thereby between the parts of the 35 workholder without severing the same from the rod, the parts of the workholder being held together under lateral pressure while the first mentioned punch is engaging the rod and separated slightly when the last 40 mentioned punch is forming the opening, and comprising a die, which engages and applies pressure to the article while on the punch that withdrew the same from said cavity.
- 5 21. In mechanism of the character described; a separable workholder having a cavity therein; a punch for upsetting the projecting portion of a rod held between the parts of the workholder, to fill said cavity; another punch separate from the first 50 mentioned punch for forming an opening in said upset portion that forces the material engaged thereby between the parts of the workholder without severing the same from the rod, the parts of the workholder being held together under lateral pressure while the first mentioned punch is engaging the rod and separated slightly when the last 55 mentioned punch is forming the opening, the punch last referred to during its withdrawal carrying with it, and out of its cavity, the article formed therein; means for trimming said article after it has been removed from the workholder; and die means 60 for applying pressure to one face of the 65 article after the same has been removed from the cavity, the axes of the trimming and die means being substantially coincident with each other.
22. In mechanism for forming an article 70 from a rod in a workholder; means for withdrawing the article so formed from said workholder, comprising a punch or the like; means for stripping the article from said punch, comprising a mechanism having members movable radially from a common center and so formed as to have an opening around said common center, which members yield when an article on a punch is moved therethrough in one direction but remain rigid while the punch is being moved in the opposite direction and by reason thereof stripping the article from the punch; means for trimming said article after it has been 75 removed from the workholder; and die 80 means for applying pressure to one face of the article after the same has been removed from the cavity, the axes of the trimming die, die means and opening in the stripper mechanism being substantially coincident 85 with each other.
23. In mechanism for forming an article 90 from a rod in a workholder; means for withdrawing the article so formed from said workholder, comprising a punch or the like; means for stripping the article from said punch, comprising mechanism having members movable radially from a common center and so formed as to have an opening 95 around said common center, which members yield when an article on a punch is moved therethrough in one direction but remain rigid while the punch is being moved in the opposite direction and by reason thereof stripping the article from the punch; means for trimming said article after it has been 100 removed from the workholder; and die means for applying pressure to one face of the article after the same has been removed from the cavity, the axes of the trimming die, die means and opening in the stripper mechanism being substantially coincident 105 with each other.
24. In mechanism of the character described; a separable workholder having a cavity therein; a solid punch for upsetting the projecting portion of a rod between the parts of the workholder to fill said cavity; another solid punch separate from the first mentioned punch for forming an opening in said upset portion that forces the material engaged thereby between the parts of the workholder without severing the same from the rod, the parts of the workholder being held together under lateral pressure while the first mentioned punch is engaging the rod and separated slightly when the second 110 mentioned punch is forming the opening.

- and means for moving said punches whereby they are each successively moved into and out of a position wherein their axes are coincident with that of the said cavity.
5. 25. In apparatus of the character described; companion dies movable toward and away from each other; and means for intermittently feeding a rod between said dies, said feed mechanism permitting a limited reverse movement of the rod between the dies.
10. 26. In apparatus of the character described; die mechanism; and means for intermittently feeding a rod through the die mechanism, comprising in part companion feed rolls, a rock member operatively connected with one of the rolls, and a member through which motion is imparted to the rock member, said member being so connected with the rock member that the latter may have independent movement relatively thereto.
15. 27. In apparatus of the character described; die mechanism; and means for intermittently feeding a rod through the die mechanism, comprising in part companion feed rolls, a rock member operatively connected with one of the rolls, a member, through which motion is imparted to the rock member, and having a connection therewith whereby it may move a limited distance in one direction without imparting movement to the rock member.
20. 28. In an apparatus of the character described; die mechanism; and means for intermittently feeding a rod through the die mechanism, comprising in part companion feed rolls, a rock member operatively connected with one of the rolls, a member, through which motion is imparted to the rock member, and having a connection therewith whereby it may move a limited distance in one direction without imparting movement to the rock member, and yielding means for normally holding the member and rock member in one of their relative positions.
25. 29. In apparatus of the character described; die mechanism; and means for intermittently feeding a rod through the die mechanism, comprising in part companion feed rolls, a rock member operatively connected with one of the rolls, a member through which motion is imparted to the rock member, and a pin fixed in one of the members and projecting through a slot in the other of said members, and forming a slip joint connection therebetween.
30. 30. In apparatus of the character described; die mechanism; means for intermittently feeding a rod through the die mechanism, comprising in part companion feed rolls; a rock member operatively connected with one of the rolls, a member through which motion is imparted to the rock member, a pin fixed in one of the members and projecting through a slot in the other of said members, and forming a slip joint connection therebetween; and a spring fixed to both of said members that exerts its tension so as to hold the said pin at one of said slots.
35. 31. In mechanism of the character described, having a workholder; feed means for advancing a rod therethrough; and means for performing an operation upon said rod that will cause the same to pass through said workholder in a direction opposite to the aforesaid feed movement, the feed means being so arranged as to yield sufficiently to permit this reverse movement.
40. In testimony whereof, I have hereunto affixed my signature.

RICHARD LESTER WILCOX.
